UNITED STATES PATENT OFFICE.

ALBERT HONEGGER, OF RUTI, SWITZERLAND, ASSIGNOR TO MASCHINENFABRIK
RUTI FORMERLY CASPAR HONEGGER, OF RUTI, SWITZERLAND.

OPERATING MECHANISM FOR POWER-DRIVEN LOOMS.

1,418,646.

Specification of Letters Patent. Patented June 6, 1922.

Application filed August 24, 1921. Serial No. 494,783.

To all whom it may concern:

Be it known that I, ALBERT HONEGGER, a citizen of the Republic of Switzerland, residing at Ruti, in the Canton of Zurich and 5 Republic of Switzerland, have invented certain new and useful Improvements in and Relating to an Operating Mechanism for Power-Driven Looms (for which I have filed applications in Switzerland on June 22, 10 1920, application No. 6464; in Germany on June 30, 1920, application M. 69,885,) of which the following is a specification.

In power driven looms having stationary shuttle boxes and a moving batten, the great 15 drawback has been met with, more particularly in the case of high speeds, that the batten at the end of its backward swing cannot be stopped sufficiently quietly, so that the reed is not set in exactly the correct position with regard to the shuttle box and therefore, on the shuttle passing through the 20 shed, disturbances occur, that is, the shuttle is deflected from its proper path and causes damage.

25 The object of the invention is to obviate this drawback and to cause the periodic starting and stopping of the crank shaft and hence of the batten to be free from jerk without the co-action of toothed gearing.

30 Partially toothed wheels have already been used for moving the batten or the weft beating device by means of a crank, no means, however, being provided for causing the crank shaft to start and stop without a jerk. In the present driving device partially toothed wheels are also used, but the 35 object mentioned above is realized by pins or rollers fitted to the driving wheel co-acting with a running-up surface and a retaining surface of a member, which is in operative connection with the crank shaft.

The accompanying drawing shows a constructional example of the invention.

45 Figs. 1 and 2 are a side elevation and a plan view of a power driven loom with the driving mechanism and showing the batten in its back position.

Figs. 3 and 4 are similar views showing the batten in its forward position.

50 Fig. 5 is a front elevation of the loom.

Figs. 6 to 10 show the driving mechanism in different positions and

Figs. 11 and 12 are an end elevation of the device shown in Fig. 8 and a plan view of the same.

The driving wheel 2 is fixed on the driving shaft 1, which is journalled in the lower part of the machine frame (Figs. 1, 3 and 5). The driving wheel is provided with teeth, which are interrupted on two diametrically opposite parts of the circumference (Figs. 8-12), two guiding grooves 3, 4 adjacent to the toothless parts of the circumference of the wheel 2, which are concentric with the axis of the wheel, two pairs 60 of rollers 5, 6 and 7, 8 mounted on arms, which rollers are arranged laterally of the teeth in the neighbourhood of the four last teeth, two ascending guiding surfaces 9, 10, each one laterally at each running out end 70 of each guiding groove 3, 4 and two pairs of cam surfaces 11, 12 and 13, 14 adjoining the end teeth of the toothed part of the wheel.

On the crank shaft 15 there is a pinion 16, the teeth of which are interrupted at one 75 point only, and which is provided with two rollers 17, 18 fitted in the neighbourhood of the end teeth of the pinion on its inner side and with two bent forked arms 19 and 20 on its outer side opposite the interrupted 80 part of the pinion teeth, which comprises two teeth. Connecting rods 21 connect the crank shaft 15 with the batten supports 22 in the usual manner. The shuttle boxes 23 are fixed to the end frames 24 of the loom. 85

In connection with Figs. 1-5 the action of the drive on the batten shall now be described and in connection with Figs. 6-10 the sequence of operations on the periodic starting and stopping of the crank shaft or the 90 engagement or disengagement of the teeth of the wheels 2, 16.

In Figs. 1 and 2 the batten L is in the rear position and it is assumed that the shuttle has run into one of the shuttle boxes. On 95 the driving wheel 2 rotating in the direction of the arrow α (Fig. 1), the roller 7 of the wheel 2 will strike the arm 19 of the forked lever 19, 20, before the engagement of the wheels 2 and 16 and will give the toothed pinion 16 an initial rotation. The wheels 2 and 16 will thereupon come into engagement and the crank shaft 15 will be given a complete revolution by one toothed portion of

the wheel 2. Figs. 3 and 4 show the batten L in the front position, that is, when beating the weft. At each half revolution of the wheel 2 the batten L is moved forwards and backwards and remains in its rear position until the shuttle has run from one shuttle box into the other. To one revolution of the driving shaft 1 the batten makes two backward and forward movements.

10 In Fig. 6 the roller 5 of the wheel 2 is about to press on the arm 19 of the forked lever 19, 20 and thereby to give the toothed pinion 16 the initial rotation free from jerk. On this movement taking place the roller 17 of the pinion 16 comes out of the outwardly enlarged exit opening 4^a, see Fig. 6, of the guiding groove 4, which prevents an unintentional rotation of the pinion 16, while the roller 18 of the toothed pinion 16 slides along 15 the descending curved surface 9 until the first tooth of the toothed portion of the wheel 2, which now comes into operation, engages the first tooth of the toothed pinion 16, which has already commenced to rotate. 20 Through the roller 18 and the curved surface 9 an acceleration of the toothed pinion 16 is prevented, when the machine is running at a high speed, and a correct meshing of the wheels 2 and 16 is effected without a 25 jerk. In order to enable the guiding grooves 3, 4, which project radially over the teeth of the wheel 2, to rotate under the toothed pinion 16, the hub of the toothed pinion 16 and the crank shaft 15 are recessed at 15^a. 30 Fig. 7 shows the position in which the roller 18 leaves the curved surface 9, the meshing of the teeth of the two wheels 2 and 16 commences and the initial rotation of the toothed pinion 16 by means of the roller 5 and the lever arm 19 stops. Fig. 9 shows the position in which the last tooth of the toothed pinion 16 still meshes with the wheel 2 and the roller 17 of the toothed pinion 16 is about to enter the guiding groove 3 of 40 the wheel 2. The arm 20 of the forked lever 19, 20 strikes the roller 6 of the wheel 2, which prevents an acceleration of the toothed pinion 16 and causes the pinion 16 to run out without a jerk. On the wheel 45 2 continuing to rotate, the last tooth of the pinion 16 leaves the last tooth of the wheel 2 and the pinion 16 is given its final rotation, when the roller 17 runs over the rounded entrance end of the inner surface of the 50 guiding groove 3.

Fig. 10 shows the position in which this final rotation of the toothed pinion 16 and thus its full rotation through 360° has been completed and the roller 17 has entered the guiding groove 3. The toothed pinion 16 is now secured against any involuntary rotation.

On the rotation of the wheel 2 being reversed, the roller 6 of the wheel 2 presses on 65 the arm 20 of the forked lever 19, 20 and the

roller 18 of the toothed pinion 16, which is slightly further away from the wheel 2 than the roller 17 (Fig. 12), by running up on to the laterally projecting edge of the inner part of the guiding groove 3 or 4, prevents the toothed pinion 16 from rotating further, after it has made its complete revolution.

The curved surfaces 11, 12, 13 and 14 of the wheel 2 have the object of acting on the last tooth of the toothed pinion 16 when turned in one or the other direction and of thus preventing the last tooth of each toothed portion of the wheel 2 when turned in one or the other direction from being badly worn.

It will be seen from the above that through the co-action of the wheels 2 and 16 with interrupted teeth it is possible to obtain a periodic starting of the crank shaft without a jerk and a periodic stopping of the crank shaft without a blow. The means for starting the toothed pinion without a jerk and for gently stopping the same may be other than those shown.

The driving mechanism described makes it possible to set the batten accurately in its 90 rear position and to work at a high speed through the accurately limited rotation of the crank shaft without a jerk, without there being any fear of the shuttle being deflected from its proper course.

What I claim is:

1. A power driven loom comprising stationary shuttle boxes and a movable batten, a crank shaft, a partially toothed pinion mounted on the crank shaft, a driving wheel having two diametrically opposed toothed portions meshing alternately with said pinion, a member in operative connection with the crank shaft having an inclined surface thereon, and rollers mounted on the driving wheel at the ends of each toothed portion thereof, the rollers at one end of each toothed portion of the driving wheel being capable of acting upon one of said inclined surfaces and of running up said pinion and the roller at the other end of each toothed portion of the driving wheel being capable of receiving the push of the other inclined surfaces and of retaining said pinion.

2. A power driven loom comprising stationary shuttle boxes and a moving batten, a crank shaft, a partially toothed pinion mounted on the crank shaft, a driving wheel having opposed toothed portions meshing alternately with said pinion, a member in 115 operative connection with the crank shaft having an inclined surface, rollers mounted on the driving wheel at the ends of said toothed portions thereof, the rollers at one end of each toothed portion of the driving wheel being capable of acting upon one of said inclined surfaces and of running up said pinion and the roller at the other end of each toothed portion of the driving wheel being capable of receiving the push of the other 120 125 130

inclined surface and of retaining the said pinion, said driving wheel having co-axial grooves therein arranged co-axial therewith, a roller fitted to the said pinion capable of 5 engaging a guiding groove of the driving wheel during the forward motion of the batten, on the pinion coming to rest, and of remaining in the groove until the driving wheel and pinion re-engage.

10 3. A power driven loom as claimed in claim 1, having guiding surfaces on the driving wheel, which are coaxial with the latter, and a second roller fitted to the pinion, which during the backward motion of 15 the batten rests, when the pinion is at rest, on such a guiding surface, as set forth.

4. A power driven loom as claimed in claim 1, having an inclined guide laterally of each groove at the end where the roller 20 leaves the groove, for the purpose of pre-

venting an acceleration of the toothed pinion on its commencing to rotate, as set forth.

5. A power driven loom as claimed in claim 2, having an inclined guide laterally of each groove at the end where the roller 25 leaves the groove for preventing acceleration of the toothed pinion when it starts to rotate.

6. A power driven loom as claimed in claim 1, having curved surfaces at the beginning and end of each partial set of teeth 30 of the driving wheel, which curved surfaces are capable of acting in a driving sense on what is the last tooth of the toothed pinion in the direction of rotation of the latter for the purpose of protecting what is the last 35 tooth of the driving wheel in the direction of rotation from getting worn, as set forth.

In testimony whereof I have affixed my signature.

ALBERT HONEGGER.
